UNITED STATES PATENT OFFICE.

PHILIP MUELLER AND ANTON C. SCHUERMANN, OF DECATUR, ILLINOIS, ASSIGNEES
TO ADOLPH MUELLER, TRUSTEE, OF DECATUR, ILLINOIS.

DRINKING-FOUNTAIN PEDESTAL.

Original application filed November 12, 1919, Serial No. 337,490. Divided and this application filed April 30, 1923. Serial No. 635,590.

To all whom it may concern:

Be it known that PHILIP MUELLER and ANTON C. SCHUERMANN, citizens of the United States, residing at Decatur, in the county of Macon and State of Illinois, have invented new and useful Improvements in Drinking-Fountain Pedestals, of which the following is a specification.

This invention relates to a new and improved type of pedestal, more particularly adapted for use with drinking fountains, in which a bubbler head and waste bowl are supported by the pedestal, and in which the pedestal is arranged so as to compactly house the supply and waste pipe connections, together with the supply valve, and its associated parts. This case, is a division, under official requirement, of applicants' pending application, Ser. No. 337,490, filed Nov. 12, 1919.

One feature of the invention is the provision of means whereby ready access may be had to the interior of the pedestal for accomplishing the necessary adjustment to the cock body, and its associated parts, and especially to permit adjustment of the stop and regulator and the pedal parts without the removal or disturbance of the pedestal. This is accomplished by means of a removable cover plate secured to the lower portion of the pedestal adjacent the cock body, the securing means for attaching the cover plate to the pedestal being of such a construction as to prevent children and unauthorized persons from tampering with the cock body or regulating mechanism.

In the drawings illustrating several embodiments of our invention,

Figure 1 is a vertical section of a drinking fountain with our pedestal secured thereto.

Figures 2 and 3 are sectional and rear elevational views respectively, of one form of hand hole cover plate.

Figures 4 and 5 are similar views of a slightly modified type of cover plate.

Figures 6 and 7 are front elevational sectional views of the hand hole and pedestal slot cover plate.

Referring to the drawings, wherein like numerals indicate like parts in the various

figures, 10 indicates a drinking fountain pedestal in which is compactly housed the base plate 11, through which extend the lower portions of a supply pipe section 12 and a waste pipe section 13. The section 12 is suitably connected to a cock body 14 having an adjustable valve stem 16 which is operatively connected with a forked lever 17 having its pedal portion 18 extending through a slot 19 in the wall of the pedestal 10.

In order that the valve may be operated at any desired level, a child's lever 20 is adapted to engage at its forward end a portion of the lever 18, so as to actuate the valve stem 16. The outer end of the lever 20 extends through a vertical slot 21 formed in the pedestal 10, and is connected by the rod 22 to an operating pedal located on the platform 23.

The bowl 24 is removably secured to the pedestal by the screws 25, while the upper section 26 of the waste pipe is held in fixed position with respect to the pedestal by the plate 27 which rests upon the lugs 28 and held in position thereon by the screw 29, which extends through the lug 30 on the nut 31.

To permit ready access to the cock body 14, and particularly the regulator or stop screw 32, the lower portion of the pedestal 10 is provided adjacent the valve with a hand hole 33, which is adapted to be closed by a removable cover plate 34 connected by the screw 35 to the cross bar 36 positioned on the opposite side of the pedestal. The screw 35 has at its inner end a flanged head to prevent the cross bar from being disconnected from the cover 34 when the screw is loosened to permit removal of these parts from the hand hole.

While the form of the invention shown discloses a child's pedal device and stand, so as to allow children to reach the bubbler head from the ground, it is quite often desirable to dispense with the child's lever 20 and when this is done, it will be necessary to provide a cover plate which will not only close the hand hole 33, but will also cover the slot 21 arranged in the pedestal 10, through which the lever 20 would normally

extend. To provide a suitable hand hole cover when the lever 20 is not employed, we have shown in Figures 6 and 7, a modified form of cover plate which consists of the cover 34 having a downwardly extending strip 37 adapted to cover the slot 21. A flanged wrench receiving screw 38 fits in a recessed portion of the cover 34 and is provided at its inner end with a flanged head 10 adapted to engage the cross bar 39. The cross bar 39 may be inserted through the hand hole 40 by arranging the arms thereof in alignment with the recesses 41 formed in the pedestal, and having its lower end to 15 register with the slot 21. When the cross bar is in this position and a wrench is applied to the square end of the screw 38, the cross bar will be turned to the position shown in dotted lines in Figure 6, with its 20 ends engaging the inner wall of the pedestal and bearing upon the stop lugs 42 formed on the inner wall. Continued rotation of the screw 38 will cause the cover plate to be closely clamped to the outer wall of the 25 pedestal, thus completely closing the hand hole and slot. It will be observed that the stop and regulator 32 is in line with the hand hole and preferably a single wrench is provided for rotating the screw 38 of the 30 cover plate 34 and the stop and regulator screw 32. The wrench receiving formation of these two parts is preferably the same, so as to obviate the necessity of different wrenches being employed for manipulating 35 these parts.

If only the operating lever 17 is used and the pedestal is not provided with the slot 21, the cover plate is preferably of the form shown in Figures 2 and 3, in which the 40 plate 43 is of crown form, and has the screw head recess 44 adapted to receive the polygonal head 45 of the freely rotatable screw 46, said screw being provided at its inner end with a tapered flange or head 47 45 adapted to engage the inwardly arched middle portion of the locking bar 48 which spans the hand hole 49, with its ends bearing against the inner wall of the pedestal. The arched form of bar 48 and the recess 50 plate 43 bring the parts close together, and permits the use of a screw 46 of minimum length as shown in Figure 2. The locking bar 48 is permanently held to the screw 46 by the flanged portion 47 above referred 55 to, while the collar 50 on the other end of the screw prevents the escape of the plate 43, so that the parts can not become separated and lost.

The plate and bar are placed in position by inserting the bar 48 through slots 51 in the periphery of the hand hole 49, with the plate 43 resting against the outer wall of the pedestal 10. Upon turning the 60 screw 46, the bar 48 will be moved to the 65 position shown in Figure 3, with the ends

of the bar bearing against lugs 52. Continual turning of the screw will draw the bar and plate together and clamp them tightly over the hand hole. In order to insure ready removal of the plate, the lugs 70 53 are preferably placed adjacent the slots 52 so that when the bar 48 is swung back to remove the cover plate, it will strike the lugs 53, and register with the slots 51, thus being readily removed without the delay 75 which would occur if it were necessary to rotate the concealed bar 48 until registry of the bar and slots were secured.

In the construction shown in Figures 4 and 5, the bar 54 is straight instead of arched and the cover plate 55 is shallower than the form just described and has its center dropped into the hand hole as shown in Figure 4. Preferably lugs 56 will be provided on plate 55 to center and lock the plate against rotation. A screw 57 couples the plate bar 54 and the plate 55, and has its outer end fitting in a recess in the plate 55 and formed so as to receive any suitable tool. The screw 57 passes through the center of bar 54 and is preferably thickened to give sufficient threaded area at its inner end, so as to prevent complete separation of the bar from the cover. Stop lugs 58 are preferably formed adjacent the slots 59 in the pedestal so as to insure registry of the bar 54 with the said slots when the cover is removed. The lugs 58 further serve as stops for the bar 54 when it is in locked position as shown in Figure 5.

It is to be understood that slight changes in design and substitution of mechanical equivalents for the various expedients disclosed may be made without departing from the spirit of the invention and the scope of what is claimed.

We claim:

1. A pedestal for drinking fountains having a hand hole provided with vertically disposed bar receiving slots, the inner wall of said pedestal having diametrically opposed stop lugs positioned at substantially right angles to said slots, a curved cover plate for said hand hole having a central recess formed in its outer face, a locking bar having an outwardly disposed arch and adapted to pass through the slots in said pedestal and engage said lugs, and a coupling bolt threaded in said bar and freely rotatable in said plate, the head of said bolt arranged to lie wholly within said recess.

2. A pedestal for drinking fountains having a hand hole provided with radially disposed bar receiving slots and a vertical opening, stop lugs in the inner wall of said pedestal adjacent the periphery of said hole, a cover plate for said hand hole having a depending portion adapted to cover said vertical opening, said cover having a central

opening and an enlarged recess in the outer wall thereof, a locking bar, and a coupling screw threaded in said bar and freely rotatable in said plate, said screw being provided at its inner end with a tapered head and its outer extremity having an annular collar to prevent complete separation of the

parts, the outer portion of the screw lying wholly within the recess formed in said plate.

In testimony whereof we have hereunto set our hands.

PHILIP MUELLER.

ANTON C. SCHUERMANN.
